(57) **CLAIM**

The ornamental design for a bottle, as shown and described.

DESCRIPTION

FIG. 1 is a perspective view of a bottle.

FIG. 2 is a rear view of the bottle shown in FIG. 1.

FIG. 3 is a left side view of the bottle shown in FIG. 1, the right side view of the bottle being the mirror image of FIG. 3.

FIG. 4 is a front view of the bottle shown in FIG. 1.

FIG. 5 is a top view of the bottle shown in FIG. 1; and,

FIG. 6 is a bottom view of the bottle shown in FIG. 1.

The broken line showing of environmental structure in the drawings is for illustrative purposes only and forms no part of the claimed design.
